DESIGN FOR A CHILD'S SWING

John A. MacKay, Detroit, Mich.

Application May 24, 1946, Serial No. 130,030

Term of patent 3½ years

(Cl. D34—15)

To all whom it may concern:

Be it known that I, John A. MacKay, a citizen of the United States, residing at Detroit, in the county of Wayne and State of Michigan, whose post-office address is 12232 W. Outer Drive, Detroit 23, Michigan, have invented a new, original, and ornamental Design for a Child's Swing, of which the following is a specification, reference being had to the accompanying drawing, forming a part thereof in which the figure is a perspective view of a child's swing, embodying my new design, a particular feature of which is the arrangement of the seat in respect to the body of the device.

I claim:

The ornamental design for a child's swing, substantially as shown and described.

JOHN A. MACKAY.
